SAFETY RAZOR WITH ADJUSTABLE BLADE EXPOSURE

Joseph Muros, Newtonville, Mass., assignor to The Gillette Company, Boston, Mass., a corporation of Delaware

Filed Feb. 17, 1960, Ser. No. 9,227
7 Claims. (Cl. 30—60.5)

This invention relates generally to safety razors and more particularly to safety razors having means for adjusting the edge exposure of the blade in accordance with the requirements or preference of the user.

The invention is herein shown as embodied in safety razors of the type employing a sectional cap in combination with a guard or other blade-supporting member for the purpose of clamping a thin flexible blade between them in shaving position. When thus clamped the blade is transversely curved and its edge projects beyond a line tangent to the cap and guard by a distance known as the edge exposure of the blade. This edge exposure may be safely varied within certain limits and many users desire to adjust their razors in accordance with their own individual preferences.

The present invention provides particularly convenient means for effecting this blade edge exposure adjustment, and preferably in a calibrated manner such that the user may readily see the extent of adjustment which he wishes to make and tell at a glance the adjusted condition of his razor. To that end, an important feature of the invention consists in a transversely movable slide having a profiled stop surface and being movable in the handle of the razor to different positions which will determine the clamping action of the cap and guard members and the degree of curvature imparted by them to the interposed blade.

These and other features of the invention will be best understood and appreciated from the following description of several preferred embodiments thereof, selected for purposes of illustration and shown in the accompanying drawings in which:

FIG. 1 is a view of a complete razor in longitudinal section and on a considerably enlarged scale;

FIG. 2 is a fragmentary view in elevation, taken at right angles to that of FIG. 1, partly in section;

FIG. 3 is a fragmentary view in longitudinal section similar to that of FIG. 1 illustrating in an exaggerated manner the relative positions of the blade clamping elements when the razor is adjusted for maximum edge exposure;

FIG. 4 is a cross-sectional view of the line 4—4 of FIG. 2;

FIG. 5 is a view corresponding to FIG. 2 and showing an adjusting slide of modified construction;

FIG. 6 is a view corresponding to FIG. 2 and showing an adjusting slide of still another modified construction;

FIG. 7 is a view in elevation taken at right angles to that of FIG. 6; and

FIG. 8 is a cross-sectional view on the line 8—8 of FIG. 6.

The razor selected to illustrate the adjusting mechanism of my invention includes in its structure a tubular handle 10 to the upper end of which is rigidly attached a hollow handle extension 11. This extension tapers slightly upwardly and carries the blade-clamping parts of the razor as will presently appear. The handle 10 is provided near its lower end with an internal annular rib 12 which makes rotary connection with a mating annular groove in an internally threaded nut 13. The nut is in threaded engagement with the lower end of a spindle 14 which passes upwardly through the hollow handle extension 11. The spindle is provided with an upper shoulder 15 and a lower shoulder 16 within the confines of the handle ex-

2

tension 11. The blade support or guard member 17 is rigidly secured to the upper end of the handle extension 11 and presents an upwardly convex blade supporting surface with rounded marginal guard.

5 The upper end of the spindle 14 is forked and fixed in the fork is a top carrier bar 18 of a spider including at each end a cross bar 19 to which the cap sections 20 are pivotally connected. These cap sections are transversely concave and cooperate with guard member 17 in transversely curving and clamping the flexible blade 21 between them. Safety razors having a blade clamping mechanism as described up to this point are described in more detail in my prior U.S. Patents Nos. 2,644,229, dated July 7, 1953, and 2,009,272, dated July 23, 1935, to 15 which reference may be had for further details of construction and manner of operation.

Referring now to FIGS. 1-4 of the drawings, it will be seen that the handle extension 11 is channeled on both sides to form channels 23 that expose a portion of the 20 spindle 14 between the shoulders 15 and 16 thereof. In the channels 23 thus provided is fitted a transversely movable U-shaped slide 22 having a profiled upper surface which supports the spindle 14 by engaging beneath its upper shoulder 15. As shown in FIGS. 2 and 4, the profiled upper surface of the slide is stepped having a low portion marked L and a high portion marked H. In FIGS. 2 and 4, the low portion L of the slide engages the upper shoulder 15 of the spindle 14. In order to bring the higher stop surface of the slide into operative position, 25 the slide is moved as indicated in FIG. 2 from the full line position therein shown to the dotted line position. The slide 22 is open at its outer end and is of sufficiently resilient material to be sprung and forced into operative relation with the spindle 14, being biased thereafter to 30 embrace the spindle between its arms so that it is frictionally retained in its adjusted position.

The construction shown in FIG. 5 corresponds with that above described except that in this case the slide 32 has its upper stop surface uniformly inclined, running 40 from its lower end where the slide is marked L through an intermediate or regular position to its higher end marked H. The slide 32 may be adjusted transversely and will be yieldingly held in whatever position of adjustment it may be placed by the user.

45 The construction shown in FIGS. 6-8 is similar to that described in connection with FIGS. 1-4 except that in this embodiment the resilient and adjustable slide 32' is provided with internal detents 33 which limit the movement of the slide to two adjusted positions and of which the intermediate detent clicks in being forced past the spindle 14. It will be observed also that in this embodiment the slide 32' is mounted in a transverse aperture 34 in the handle extension 11 rather than in the external channels shown in FIGS. 1-4, 5 although in both cases the slide is 50 U-shaped and resiliently engages opposite sides of the spindle 14.

It will be understood that by turning the nut 13 the spindle 14 with its spider and cap sections 20 are drawn 55 downward, and the cap sections flex the blade 21 over the guard 17 into positions of more and more curvature. At the lower limit of spindle movement the blade has its maximum curvature and its cutting edge has minimum edge exposure as suggested in FIG. 1. Under these conditions the position of the spindle is determined by the engagement of the spindle shoulder 15 with the low portion of the profiled face of the slide 22. The slide 22 is 60 free for movement only while the nut 13 is reversely turned and pressure on the blade relaxed. Now, when the slide is advanced to bring the high portion of its profiled face beneath the shoulder 15 of the spindle, the spindle can be drawn down a lesser amount, as suggested 65

in an exaggerated degree in FIG. 3, less curvature is imparted to the blade 21 and it is therefore clamped with a maximum degree of edge exposure. It will be understood that the separation between the cap sections 20 and the guard 17 has been greatly exaggerated in FIG. 3 for purposes of illustration and that in actual practice the blade is firmly held between the cap sections and the guard but with a lesser amount of curvature than with the razor adjusted for minimum exposure.

Having thus described my invention with particular reference to illustrative embodiments thereof, it will be obvious to those skilled in the art to which the invention pertains that various changes and modifications may be made therein without departing from the spirit and scope of my invention.

What I claim as new and desire to secure by Letters Patent of the United States is:

1. An adjustable safety razor comprising a tubular handle having at its upper end a hollow extension carrying a convex guard member, a spindle movable within the handle and the hollow extension and having a shoulder located within the extension, a stepped slide mounted in the extension for transverse movement therein engageable by the shoulder of the spindle, concave cap sections carried by the spindle, and means connected with the spindle for moving the cap sections into blade-clamping position adjustably determined by the position of said stepped slide.

2. An adjustable safety razor as defined in claim 1, further characterized in that the hollow extension has a channel therein exposing the shouldered portion of the spindle and that the stepped slide is transversely movable in said channel in engagement with the spindle.

3. An adjustable safety razor as defined in claim 1, further characterized in that the hollow extension is channeled on both sides of the spindle and that the said slide

is U-shaped and yieldingly embraces the spindle between its arms.

4. An adjustable safety razor comprising cooperating blade-clamping members, a movable spindle carrying one of said members, a handle enclosing the spindle and carrying the other member, and a U-shaped slide movably mounted in the handle, resiliently engaging the spindle and having a profiled stop surface and a series of corresponding detents defining the settings of the slide.

5. An adjustable safety razor as defined in claim 4, further characterized in that the handle includes a hollow extension apertured to receive and partially enclose the said U-shaped slide and guide its adjusting movement.

6. An adjustable safety razor as defined in claim 4, further characterized in that the U-shaped slide is resilient whereby it may be sprung over the spindle and is biased to embrace the spindle with yielding pressure.

7. An adjustable razor comprising cooperating blade-clamping members, a movable spindle carrying one of said members, a handle enclosing the spindle and carrying the other member and blade edge exposure controlling means movably mounted in the handle and having a profiled stop surface and means connected with the spindle for bringing said blade-clamping members into and out of blade-clamping relation, the spindle including stop means engageable with the profiled stop surface to limit the blade clamping movement of the spindle in accordance with the position of the blade edge exposure controlling means.
